UNITED STATES PATENT OFFICE.

CHARLES W. LITTLEFIELD, OF WATSONVILLE, CALIFORNIA.

CLOTHESPIN.

Application filed July 5, 1921. Serial No. 482,434.

To all whom it may concern:

Be it known that I, CHARLES W. LITTLEFIELD, a citizen of the United States, residing at Watsonville, in the county of Santa Cruz and State of California, have invented a certain new and useful Improvements in a Clothespin; and I do hereby declare the following to be a full, clear, and exact description of the invention, such as will enable others skilled in the art to which it appertains to make and use the same.

The invention relates generally to clips and specifically to clothes pins and more particularly to articles of this kind formed from wire.

The invention consists of a clothes pin embodying complementary members pivotally connected intermediate their ends to provide coacting jaws and operating handles, the latter normally standing apart and the jaws being pressed together by a spring action and separable by inward pressure on the handles.

The invention consists of an article of the nature aforesaid constructed of a single length of wire of suitable gage and material bent upon itself to provide a transverse coil or helix and coacting jaws and handles, said coil or helix being adapted to serve both as a spring and fulcrum and as a housing for the ends of the wire which extend therein and are concealed and protected thereby.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a perspective view of one of many forms of clothes pins embodying the invention,

Figure 2 is a plan view illustrating the blank at one stage in the formation of the pin,

Figure 3 is a view similar to Figure 2 showing a further step in forming the pin,

Figure 4 is a front view of a different form of modification,

Figure 5 is a side view of the modification shown in Figure 4,

Figure 6 is a front view of a further modification.

Figure 7 is a side view of the form of clothes pin illustrated in Figure 6,

Figure 8 is a plan section on the line 8—8 of Figure 6,

Figure 9 is a front view of a further modification,

Figure 10 is a side view thereof,

Figure 11 is a plan section on the line 11—11 of Figure 9, and

Figure 12 is a perspective view of a further modification.

Corresponding and like parts are referred to in the following description and designated in the several views of the drawings by like reference characters.

In each of the forms the article is constructed of a single length of wire bent to provide a transverse coil or helix 1, coacting jaws 2, complementary handles 3 and in-turned ends 4 which enter the coil or helix 1 and are concealed and protected thereby. The coil 1 and in-turned ends 4 are in line 80 with the fulcrum of the companion members and are substantially the same in the several forms, the differences residing chiefly in the gripping ends of the jaws, the pressure receiving ends of the handles and the relative arrangement and construction of the element comprising the pivotally connected member.

In the form shown in Figure 1 the jaws 2 are of similar or like formation and consists of loops of uniform size which are oppositely disposed. The handles 3 are substantially alike and are laterally offset to admit of the in-turned ends 4 passing between the respective members which are in direct contact therewith. Thus an element of each member pivots upon an in-turned end 4. Each of the members has a portion of the wire common to the jaw and handle and these portions are disposed at opposite ends of the coil or helix 1 and pivoted upon the respective in-turned ends 4.

The article shown in Figures 4 and 5, while embodying the same general structural features, is specifically different in the formation of the handles and the relative arrangement thereof. The handles 3^a appear as stems which terminate in eyes 3^b and constitute end portions of the wire blank from which the device is formed. The handles are centrally disposed and the elements of 110 the jaws of which they form extensions are inwardly offset, as shown at 3^c, to admit

of the handles 3^a being diametrically opposite in the same plane and fulcruming on the coil or helix 1.

The form of pin shown in Figures 6 and 7 embodies the same general construction and arrangement as that disclosed in Figure 1, the elements of the members common to both the jaws and handles pivoting on the in-turned ends 4. One of the jaws has its outer or gripping end 2^a inturned and the companion jaw is provided at its outer or gripping end with an inturned end 2^b which overlaps and cooperates with the inturned end 2^a to insure a more positive gripping action when the device is in service.

In the form shown in Figures 9 and 10 the handles 3 are substantially the same as corresponding parts illustrated in Figure 1. The general arrangement of the members is somewhat similar with the exception that one of the elements of a member common to the jaw and handle is offset inwardly as indicated at 3^d to form a narrow jaw 2^c whose gripping end 2^a is inturned to pass through an eye or elongated coil 2^e at the gripping end of the other jaw 2 and in the plane thereof. This provides for a positive grip and prevents slipping.

Figure 12 illustrates a construction in which the handles are substantially the same as those shown in Figures 1, 6 and 9 and in which one of the jaws 2^f is constructed similar to the jaw 2^c of the form shown in Figures 9 and 10. The other jaw 2 corresponds to the jaw of the clothes pin illustrated in Figure 1. The handles are similarly fulcrumed and the elements of each member common to the jaw and handle are fulcrumed upon the receptive inturned ends 4. Forms other than those herein indicated are contemplated and may be devised but are not referred to since they embody the features herein specified in different combinations and are such as come within the purview of the invention and readily suggest themselves to one skilled in the art.

In forming the pin, a wire blank of similar length, gage, temper and material is provided and doubled upon itself, the ends being bent laterally as indicated at 4 in Figure 2. A coil 1 is formed at the fold. The blank at this stage appears as shown in Figure 2. In the next step one of the end portions is bent to provide the handle 3 and cooperating jaw 2, the bent end 4 entering the coil 1. The blank at this stage is shown in Figure 3. In the final step the other folded end portion of the blank is bent to provide the other jaw and handle, thereby completing the pin which appears as indicated in Figure 1.

Having thus described the invention, what I claim is:—

1. A clothes pin of the character specified

consisting of a single length of wire comprising complementary pivoted members, each member consisting of a jaw and a handle, the article comprising a transversely disposed coil or helix coincident with the pivotal connection of the members and receiving the in-turned ends of the wire which are concealed and protected thereby, each of the members comprising an element which is common to the jaw and handle, the gripping end of one of the jaws consisting of a coil and the gripping end of the companion jaw being offset to enter the gripping coil to prevent slipping.

2. A clothes pin of the character specified consisting of a single length of wire comprising complementary pivoted members, each member consisting of a jaw and a handle, the article comprising a transversely disposed coil or helix coincident with the pivotal connection of the members and receiving the in-turned ends of the wire which are concealed and protected thereby, each of the members comprising an element which is common to the jaw and handle, the gripping end of one of the jaws terminating in a coil, and the gripping end of the other jaw being offset to enter the said coil to insure a positive gripping and prevent slipping.

3. A clothes pin of the character specified, consisting of a single length of wire bent to provide complementary pivoted members and a transversely disposed coil, or helix, coincident with the pivotal connections of the members, the end portions of the wire forming the handles and the terminals of the wire being bent in from the handles to enter the ends of the coil to provide a fulcrum for said members and against opposite sides of which coil the said members are held by the spring action of the coil under any and all relative positions of the jaws.

4. A clothes pin of the character specified, consisting of a single length of wire bent to provide complementary pivoted members and a transversely disposed coil, or helix, coincident with the pivotal connections of the members, the end portions of the wire forming the handles and the terminals of the wire being bent in from the handles to enter the ends of the coil to provide a fulcrum for said members and against opposite sides of which coil the said members are held by the spring action of the coil under any and all relative positions of the jaws, and the free end of one of said jaws being inturned to enter the other of said jaws.

In testimony whereof I affix my signature in presence of two witnesses.

CHARLES W. LITTLEFIELD.
